3 Claims. (Cl. 179—15)

The present invention relates to an arrangement at multichannel-pulse communication systems, in which the signal of the individual communications are transmitted from one subscriber place to another through a transmission medium common for the communications in the form of modulated pulses, at which each subscriber place is connected to the transmission medium over a contact, a coil connected in series with the contact and a low pass filter, whose terminals turned towards the coil are terminated by a condenser, which together with the coil forms an oscillation circuit, the natural oscillation period of which is mainly equal to double the time during which the contacts are closed for transmission of a pulse.

During a time when the switch at a subscriber place is open, the appurtenant condenser is charged through the low pass filter to a potential which is proportional to the amplitude of the momentary speech potential. When the switches, which connect two subscribers with each other, are closed, a recharge course occurs in the oscillation circuit formed by the condensers and inductances of these subscribers, so that after half a period of the resonance frequency the charges of the two condensers have changed places. In this moment the switches are opened and the charges are compensated in the pulse pause through respective low pass filter in the form of a speech current.

When feeding signals from a signal source to a time multiplex system of this kind, a signal circuit is provided with a similar oscillation circuit according to a previously known method, which oscillation circuit consists of an inductance and a condenser but not of a low pass filter since the charging of the condenser must be done in the pause between adjacent channel pulses if the signal source shall be able to be used commonly for several communications in different pulse positions (channels). The charging occurs therefore from the signal source through a circuit, which is dimensioned in a special way, and a switch (contact), which is closed during the pause between the channel pulses. This method of feeding is used especially at two-wire circuit connection between the subscribers owing to certain crosstalk problems.

At four-wire circuit connection between the subscribers with an amplifier in each line going out from the exchange it may seem possible to arrange the signal feeding in such a way that a potential source is connected to the transmission medium directly over a contact which operates coincidentally with the contact of a receiving subscriber. Since a compensating condenser is generally connected to the transmission medium this method is not applicable because for one thing the contact at the potential source can be charged too heavily in each operation moment owing to the influence of the compensating condenser, for the other a rest charge on the compensating condenser remains after each pulse, which charge requires one for the rest oversized leakage circuit so that signal crosstalk to the following channel shall not arise.

The purpose of the present invention is to eliminate said drawbacks. The invention is as mentioned especially applicable in connection with pulse communication systems operating with four-wire systems, where the information transmission is unidirectional in a transmission

2

channel and where an amplifier is connected between the transmission medium and receiving subscriber.

An arrangement according to the invention is characterized thereby that there is a signal potential source for signal feeding to a subscriber place, which signal potential source is periodically connectable to the transmission medium over an inductance and a contact and is arranged to emit together with the remaining circuit elements a potential over the series connection of the coil and the condenser, the lapse of which is mainly symmetrical in relation to the time

$\frac{\tau}{2}$

and has a minimum value for $t=0$ and $t=\tau$, that the inductance value of said inductance falls below the inductance value of said coil, and that the closing time of the contact connected between the signal potential source and the transmission medium falls below the time τ .

FIG. 1 shows an embodiment of the invention; and

FIG. 2 shows some of the wave forms used in describing the embodiment of FIG. 1.

In FIG. 1 an electronic telephone exchange operating according to the time multiplex principle is shown, in which only two subscribers Ab_1 , Ab_2 in a four-wire system are shown and only one transmission direction has been drawn in this system, one from Ab_1 to Ab_2 . The subscribers Ab_1 and Ab_2 belong to two different groups of subscribers, one group of which is connected to a transmission conductor T_1 and the other to a transmission conductor T_2 . The subscriber Ab_1 is over a low pass filter LP_1 , a condenser C_1 , an inductance L_1 and an electronic switch K_1 connected to the transmission conductor T_1 , at which the condenser C_1 is a part of the last link of the low pass filter. In a similar way the subscriber Ab_2 is connected over a low pass filter LP_2 , a parallelly connected condenser C_2 , an inductance L_2 and an electronic switch K_2 to the transmission conductor T_2 . Furthermore, there is an amplifier F_2 between the low pass filter LP_2 and the subscriber Ab_2 for compensation of the attenuation in the transmission medium connected between the subscribers, which thus consists of the transmission conductors T_1 and T_2 and an electronic group switch K_g connected between them.

At transmission from Ab_1 to Ab_2 the switches K_1 , K_g , K_2 are synchronously and periodically closed during a time $\tau=\pi\sqrt{L \cdot C}$, where L represents the inductance value of each one of the inductances L_1 and L_2 , and C represents the capacitance of each one of the condensers C_1 and C_2 . When the switches K_1 , K_g , K_2 are open, charge enters to the condenser C_1 through the filter LP_1 and as the switches are closed during the time τ this charge oscillates over to the condenser C_2 and is then conducted further through the filter LP_2 to the amplifier F_2 and the subscriber Ab_2 during the following pause. In order to eliminate the disturbing influence from the stray capacitances of the transmission medium, the condensers C_1' and C_2' are connected to the transmission conductors and dimensioned with regard to said stray capacitances so that the total capacitance between the conductors (the transmission medium) and earth fulfills the relation

$$C_1' + C_2' = \frac{2C}{3}$$

or

$$C_1' + C_2' = \frac{2C}{15}$$

Hereby is obtained that when the current through the switches K_1 , K_g , K_2 is zero and they are disconnected, the potential of C_1' and C_2' is also zero except for possible

small rest charges, which remain owing to the attenuation of the oscillation circuits, and which are removed during the pause between two channels by aid of periodically operating electronic short circuiting contacts K_1 and K_2 .

At the top of FIG. 1 a method is indicated for signal feeding by aid of a signal potential source U with a negligible inner impulse impedance (in the example indicated as a direct voltage battery), which directly over a contact K_s in coincidence with the contact K_2 of the receiving subscriber is periodically connectable to the transmission conductor T_2 . In this way, however, strong charging currents to the condenser C_2 are obtained through the contact K_s , which can entirely spoil this contact, and furthermore the condenser C_2' is charged to the potential amplitude of the potential source U . This charge, which during certain circumstances is rather large, must be removed during the pause to the next channel in order to avoid signal cross-talk between the channels, and to do this considerable measures would have to be taken. Therefore the signal input ought instead to be arranged according to the invention, which now will be described in detail.

Signal input occurs at the transmission conductor T_2 and for this purpose there is an input circuit consisting of an input switch K_{s2} , a series inductance L' and a signal source, which has a negligible inner impulse impedance and also here indicated in the form of a direct current battery with the potential V for the sake of simplicity. The current switch K_{s2} is actuated, i.e. is closed, during a time $\tau' < \tau$. At signal feeding the group switch K_g is inhibited and signal is thus fed only to the subscriber A_2 over T_2 , K_2 , L_2 , LP_2 and F_2 .

In order to obtain a good signal feeding the following requirements have to be put on the shown system:

- (1) At the time $t=\tau$, i.e. the opening moment of the switch K_2 , the current through the switch shall have a zero passage at the same time as the potential of the condenser C_2 has a maximum.
- (2) At the same moment the potential of the condenser C_2' shall have a minimum and be at or at least be near the zero value.
- (3) At release of the switch K_{s2} the current through it shall have a minimum value at or at least near zero, preferably a zero passage.

The first requirement is met if a potential function is generated over the condenser C_2' , which potential function is symmetrical in relation to $\tau/2$. Especially suitable for this purpose are the symmetrical potential functions, which have a minimum value at the beginning and at the end of the time τ , since these functions already meet the second requirement. Such potential functions are for example the functions:

$$U=U_0(1-\cos n\omega t) \quad n=1, 2 \dots$$

$$\omega = \frac{2\pi}{\tau}$$

Such a potential function with $n=1$ appears for example at ordinary transmission from A_1 to A_2 if

$$C_1' + C_2' = \frac{2C}{3}$$

with $n=2$ such potential function is obtained if

$$C_1' + C_2' = \frac{2C}{15}$$

If the subscriber A_2 for a moment is left out of account, the cosine functions indicated hereabove can be generated by dimensioning the inductance L' and the condenser C_2' according to the following relation:

$$\tau = 2 \cdot n \cdot \pi \cdot \sqrt{L' \cdot C_2'}$$

The subscriber A_2 , which in reality is connected over L_2 , C_2 , will, however, disturb the indicated potential

function by that it draws out energy from the circuit L' , C_2' and therewith attenuates the potential function so that the minimum values do no longer appear at zero. The attenuation is less with increased impedance relation between the LC-combination of the subscriber circuit and the charge circuit, i.e. the relation

$$\sqrt{\frac{L_2}{C_2}} : \sqrt{\frac{L'}{C_2'}}$$

ought to be chosen as large as possible. At choice of C_2' the system dimensioning is confined, and from symmetry reasons C_1' and C_2' are wanted equal in size, which gives

$$C_2' = \frac{C}{3}$$

The dimensioning of L' is then determined by the choice of n in the potential function. From practical reasons n cannot be chosen larger than 2, because L' would then be too small and currents in the input circuit too large. An approximative estimate of L' is therefore made from the relation:

$$2 \cdot 2 \cdot \pi \sqrt{L' \cdot \frac{C}{3}} = \tau = \pi \sqrt{LC}$$

$$\therefore L' \approx \frac{L}{5,3}$$

where L thus is the inductance value of L_2 respectively L . However, with this dimensioning the influence of the subscriber circuit is still too great. The relations are considerably improved if the switch K_{s2} is disconnected not at the time τ but earlier, that is at a time τ' when the current through K_{s2} has a minimum value near zero, whereby the requirement mentioned above is met. The charge remaining in the condenser C_2' at the time τ' is derived to the oscillation circuit of the subscriber A_2 during the time $\tau - \tau'$, which thereby rectifies the potential function over the condenser C_2' so that the requirements 1 and 2 hereabove are met.

With

$$C_2' = \frac{C}{3}$$

L' becomes hereby somewhat smaller than previously mentioned, that is

$$\frac{L}{6,2}$$

At this τ' takes about $\frac{1}{5}$ of the time τ .

The now related course is schematically shown in FIG. 2, which shows the potential VC_2' over the condenser C_2' , the current IK_{s2} through the switch K_{s2} , the potential VC_2 over the condenser C_2 and the current IK_2 through the switch K_2 as functions of the time t . As appears the potential VC_2' and the current IK_2 have minimum values for $t=\tau$, while the current IK_{s2} has a minimum value for

$$t=\tau' = \frac{1}{5}\tau$$

I claim:

1. In a time-multiplexing system wherein a number of subscribers are connectable to a communication line, an inductance, filter means having a shunt capacitor forming together with said inductance an oscillator circuit, switching means for connecting said line to each subscriber through said inductance and filter means, said switching means being closed and opened at a time τ to transmit a pulse between two subscribers and said oscillator circuit having a natural oscillation period which is substantially twice time τ , a common charging circuit for charging said oscillator circuit of one of said subscribers, said charging circuit comprising a signal source and an inductance, switching means for connecting the charging circuit to the communication line, said signal source providing a signal pulse symmetric over sub-

stantially half of time τ and having minimum amplitudes at zero time and time τ , respectively, across the oscillator circuit of a subscriber when said subscriber is connected to the communication line through the switching means and said charging circuit is connected to the communication line for a time less than τ , the value of said inductance in said charging circuit being less than the value of said inductance in said oscillator circuit of said subscriber.

2. In a time multiplexing system wherein a number of subscribers in a first subscriber group are connectable to a first communication line, a number of subscribers in a second subscriber group are connectable to a second communication line, switching means for connecting said first and second lines, switching means for connecting said first line to each subscriber of said first group, a first inductance, first filter means having a shunt capacitor forming together with said inductance an oscillator circuit, switching means for connecting said second line to each subscriber of said second group, a second inductance, second filter means having a shunt capacitor forming together with said second inductance an oscillator circuit, said switching means for connecting the subscribers' communication lines being periodically closed and opened together at a time τ to transmit a pulse between a subscriber of said first group and a subscriber of said second group, and said oscillator circuits having a natural oscillation period which is substantially twice time τ , a common charging circuit for charging said oscillator circuits of said subscribers connectable to one of said communication lines, said charging circuit comprising a signal source and an inductance, switching means for connecting the charging circuit to one of said communication lines, said signal source providing a signal pulse symmetric over substantially half of time τ and having mini-

5 mum amplitudes at zero time and time τ , respectively, across the oscillator circuit of a subscriber when said subscriber is connected to said one of said communication lines through the respective switching means and said charging circuit is connected to said one of said communication lines for a time less than τ , the value of said inductance in said charging circuit being less than the value of said inductance in said oscillator circuit of said subscriber.

10 3. In a time multiplexing system as set forth in claim 2, wherein the value of said inductance in said charging circuit is equal to substantially

$$\frac{L}{6.2}$$

15 where L is the value of said inductance in said oscillator circuit, and said charging circuit is connected to said second line for a time substantially $\frac{1}{6}$ of time τ .
